UNITED STATES PATENT OFFICE

2,045,744

GASKET MAKING APPARATUS

Albert Wood, Battle Creek, Mich.

Application December 28, 1933, Serial No. 704,217

5 Claims. (Cl. 164—61)

This invention relates to gasket making apparatus, and more particularly to an improved apparatus for punching and cutting gaskets from sheet stock.

5 It is an object of the present invention to provide a comparatively small compact machine in which all of the necessary operations for cutting and punching gaskets of various shapes and sizes may be easily and conveniently performed in a single 10 machine, the mechanism for all operations deriving power from a single prime mover.

A further object is to provide a simple and efficient combined feeding and cutting mechanism wherein sheet material and particularly material 15 of varying thickness or sheets of different thickness suitable for the manufacture of gaskets may be automatically fed through the machine and simultaneously cut on any predetermined outline at the will of the operator. Also, in which the 20 feeding and cutting operations may be quickly started or stopped by engagement or disengagement respectively of the cutters and feeding 25 means with or from the material without interrupting the power transmission, or in which the power transmission may be interrupted either independently of or simultaneously with the disengagement of the feeding and cutting mechanism.

Means is also provided for varying the rate of feed of the gasket material and simultaneously 30 varying the cutting speed of the cutters.

The present invention also provides a simple, compact and efficient cutting and feeding mechanism in which the cutting and feeding members are so constructed and related that the cutting and feeding operations are synchronized in a manner whereby the outline of a gasket or other pattern on suitable sheet material may be easily held in alignment with the cutter during the cutting operation.

40 It is also an object to provide improved punching mechanism in combination with a cutting mechanism in a single compact machine and in including complete unitary interchangeable punch devices, each including a punch and die and holder 45 frame therefor, and which can be quickly interchanged in the power-driven punch-operating portion of the apparatus.

Further objects will be apparent from the specification and the appended claims.

50 In the drawings:

Figure 1 is a side elevation of a gasket cutting and punching machine, and illustrates one embodiment of the invention.

55 Fig. 2 is a left-end elevation of the embodiment illustrated in Fig. 1.

Fig. 3 is a top plan view of the machine.

Fig. 4 is a fragmentary front elevation of the cutting portion of the device.

Fig. 5 is a vertical section taken on a line corresponding to line 5—5 of Fig. 4.

Fig. 6 is a side elevation of the cutters in cutting relation.

Referring to the drawings in detail, the embodiment illustrated comprises a frame 1 in which is mounted a large part of the transmission mechanism of the device. On this frame is mounted a casting 2 having outwardly extending spaced upper and lower fixed jaws 3 and 4. These jaws extend outwardly and provide a deep throat therebetween for the passage of sheet material.

15 A horizontal cutter shaft 5 is mounted adjacent the upper arm 3 and extends through the rear of the casting 2 and is provided with a bearing therein.

A driven friction disc 6 is secured to the rear end of this shaft 5 and is located between the 20

spaced rearwardly extending portions 7 of the member 2. A transverse shaft 8 is mounted in

bearings 9, these bearings being slidably mounted in the rearwardly extending arms 7 and normally

retained in their outward position by means of 25

springs 10. The transverse shaft 8 is provided with a driving friction wheel 11, which is splined

thereon for movement across the face of the disc and suitable means is provided under the control

of the operator whereby the shaft 8 and its slid- 30

able bearings 9 may be moved laterally toward the disc 6 to bring the friction wheel 11 into en-

gagement therewith. The shaft 8 is driven from a prime mover through a suitable transmission.

35 In order to move the driving friction wheel 11 across the face of the driven friction disc 6, whereby any desired speed in either direction

may be obtained for the shaft 5, a threaded rod 12 is rotatably mounted in parallel relation with

the shaft 8, and a bracket 13 is threaded thereon 40

and engages the friction wheel 11 in such a man-

ner that by rotating the rod the driving wheel 11

may be positioned in any desired relation to the

face of the driven disc 6. A hand wheel 14 is

secured to the threaded shaft 12 for the adjust- 45

ment thereof.

As previously stated, the driving friction wheel

11 is normally out of contact with the driven disc 6, and in order to move the shaft 8 laterally

to bring the wheel into driving contact with the 50

disc, a vertical lever 15 is pivoted at 16 and is

forked at its upper end and the arms of the

forked portions are connected to the slidable

bearings 9 by means of studs 17. A foot lever 18

is pivoted on the lower part of the frame at 19 55

and connected by a pin and slot connection to a bell-crank lever 20 pivoted at 21 and in turn connected to the vertical lever 15 by means of a link 22. By means of this lever and link mechanism, 5 when the foot pedal 18 is manually operated, the bearings 9 together with the shaft 8 will be moved rearwardly against the compression of the springs 10 and the driving wheel 11 will thereby be brought into driving relation with the friction disc 6. A pulley 23 is secured to the shaft 8 and is driven from a motor 24 through speed reducing pulleys 25 and 26 and belts 27 and 28 respectively mounted thereon.

The prime mover is preferably a motor pivotally mounted at 29 to maintain a suitable belt tension, and the belt 28 may be provided with a tensioning idler 28^a controlled by spring 30.

The pulleys 25 and 26 are rigidly secured to a shaft 31 on which a combined pulley and clutch member 32 is loosely mounted, as particularly illustrated in Fig. 2. This loosely mounted clutch member 32 may be driven from the shaft 31 simultaneously with the driving of the cutter shaft through the previously described mechanism, 25 when desired.

A driving clutch member 33 is splined on the shaft 31 and may be moved into driving engagement with the combined pulley and clutch member 32 by means of a foot pedal 34, which is pivoted at 35 and connected to the clutch member 33 by link 36, bell-crank 37, and lever 38, in a manner to move the clutch member 33 into driving relation with the clutch member 32 when the foot pedal 34 is depressed.

35 A punch holding frame 34^a is mounted at the rear of the frame 1 and substantially under the friction disc 6. Interchangeable punch mechanisms 35^a may be mounted in this punch-holding frame and each comprising a suitable support 36^a in which a punch 37^a is mounted for cooperation with a suitable die 38^a also mounted therein. The punch is provided with a head 39 and is normally held in its raised position by means of a spring 40. These punch and die units may be provided with punches and dies of different sizes and are interchangeable in the support 34 and are secured therein by means of a bolt 34^b.

40 A lever 41 is pivoted at 42 in the support 34 and is provided with a cam surface engaging the head 39 of the punch, whereby a downward movement of the lever 41 will operate the punch. This lever 41 may be controlled by means of the foot pedal 34 which, as previously stated, may be operated to cause the engagement of the clutch members 32 and 33. When the clutch members are engaged a pulley 43 will be driven therefrom through a belt 44. The pulley 43 is secured to a shaft 45 on the opposite end of which is secured a cam 46, which is in operative engagement with a lever 47 pivoted at 48, the opposite end of this lever being connected to a lever 49 pivoted at 50, by means of a link 51. The lever 49 engages the end of the punch lever 41 and it will be apparent that when the foot lever 34 is operated, the clutch members 33 and 32 will be engaged and a single rotation of the cam 46 will cause the operation of the punch unit 35^a through the mechanism just described.

45 As previously stated, the cutter shaft 5 may be rotated at any desired speed and in either direction through the friction drive mechanism. This shaft extends forwardly and has a rotary disc cutter 52 secured thereon. A feed wheel 53 is secured adjacent the cutter and preferably has a radius shorter than the radius of the cutter by

substantially the thickness of the thickest material to be cut. A second rotary cutter 54 is mounted below the cutter 52 and in shearing relation therewith and in parallel relation. A second friction feed wheel 55 of substantially the same 5 diameter as the friction cutter 54 is mounted adjacent thereto.

The cutter 54 and the friction wheel 55 may be made integral, if desired, as shown in Fig. 5, and is pivoted at 56 in a vertically slidable member 57, which latter is mounted in the lower arm 4 of the member 2 and normally maintained in raised position by means of springs 58 whereby the two cutters are in shearing relation. The slidable member 57 is provided with a downwardly extending portion 59 on which is pivoted a handle 60 having a cam portion 61 bearing against the lower surface of the arm 4. When this handle and cam portion are in the position shown in Fig. 4, the cutter 54 and adjacent feed wheel 55 will be normally held in raised or cutting and feeding position by the springs, and when the handle 60 is turned to the position shown by dotted lines in Fig. 4, the cam portion 61 operates to force the cutters and their support 25 downwardly against the resistance of the springs and out of cutting and feeding relation.

50 In order to introduce the sheet stock between the cutters and feed wheels, it is only necessary to move the handle 60 into the position shown in Fig. 4. The handle may then be raised and the cutters will be forced together by means of the springs 58 and the feed wheels 53 and 55 will engage on opposite sides of the sheet stock. The feed wheel 53 being in intimate frictional engagement with the upper surface of the stock and driven by the shaft 5 through the mechanism previously described, will then, through the pressure of the sheet stock, drive the lower feed wheel and its associated cutter. The feed wheels may 40 be knurled or otherwise provided with friction surfaces.

55 The feeding wheel 53 and associated cutter are preferably either integral or assembled as a rigid unit. This construction combined with the preferably integral or rigidly assembled construction of the feed wheel 55 and cutter 54 provides a device in which the feeding is synchronous with the cutting and, as the driving of the feed is accomplished solely by the upper feed wheel 53, the outline of the gasket or other pattern to be cut is more easily held in alignment with the cutter during the cutting operation.

The cutter 54 preferably comprises an extension of the feed wheel 55 and is provided with an angular groove 56 having its vertical wall in shearing relation with the flat side of the cutter 52. The outwardly extending cylindrical portion provides a support for the trimmed portion of the material indicated by the reference character A.

60 The present device is adapted to cut gaskets of any desired shape, and, for the purpose of cutting circular gaskets, a rod 62 is mounted below the shaft 5 and parallel therewith, and an adjustable centering pin 63 is slidably mounted thereon and may be moved to any desired position and rigidly secured by means of a thumb screw 64. By this means, it is only necessary to adjust the centering pin to a desired radius, 70 punch a hole in the sheet stock, place the stock between the cutters and over the center pin 63 and rotate the stock on the pin. The cutters will then cut the stock to the diameter of a circle to which the center point 63 has been adjusted. 75

Modifications may be made in the embodiment herein described without departing from the spirit of the invention, and I therefore desire to be limited only by the prior art and the scope 5 of the appended claims.

Having thus described my invention, what I claim and desire to secure by Letters Patent is:

1. In an apparatus of the character described, a frame, a prime mover, a punch-actuating transmission mounted on said frame, a unitary punch mechanism for punching sheet material readily removable and replaceable with respect to said punch-actuating transmission and comprising a base, a reciprocable punch mounted in said base, and a die carried by said base and cooperating with said punch, manually operable means for connecting and disconnecting said punch actuating transmission with respect to said punch mechanism, said punch mechanism and frame being provided with cooperating positioning means to insure the correct positioning of said unitary punch mechanism with respect to said punch-actuating transmission, a power driven mechanism for feeding and cutting said sheet material, transmission for operating said feeding and cutting mechanism, and manually operable means for connecting and disconnecting said transmission with respect to said feeding and connecting mechanism.
2. An apparatus for cutting sheet material comprising a frame having a pair of elongated jaws unconnected with each other at one end forming a deep throat open at one end to receive the sheet material, a pair of rotatable circular cutters mounted at the open end of said frame and cooperating to cut said sheet material passed therebetween, a shaft mounted on and extending longitudinally of said frame, one of said cutters being driven from said shaft, a sheet-feeding roller driven from said shaft, having a relatively narrow feeding face whereby the sheet material may be handled to effect a curvilinear cut, a motor, driving means from said motor to said shaft, and means including a pedal for connecting and disconnecting said driving means with respect to said shaft whereby a single operator can tend the machine, using both hands to handle the sheet material and using the foot for starting and stopping the cutting and feed of the sheet, said driving means comprising a friction disc mounted on said shaft, and a friction wheel for driving said friction disc, said connecting and disconnecting means comprising means for moving said friction wheel into and out of engagement with respect to said disc.
3. Apparatus for cutting gaskets from relatively large sheets comprising a frame having a deep horizontal throat open at one end to enable the in-
- sertion of the main body of the sheet into the throat, a horizontal cutter shaft extending longitudinally of the horizontal throat, a circular cutter mounted on said shaft adjacent the open end of the throat, driving means from said shaft adjacent the other end of the throat, a feed wheel mounted on said shaft adjacent said cutter, a second feed wheel opposite said first wheel and driven from said first feed wheel through the inner position of said sheet, a second circular cutter rotatable with said second feed wheel and cooperating with said first cutter, and manually operable means for shifting said second feed wheel and second cutter from a position in which the cutters are in overlapping shearing relation to a position in which the feed wheels and cutters are separated from each other to enable the insertion of the main body of the sheet between the cutters and feed wheels into the throat of the apparatus.
4. Apparatus for cutting gaskets from relatively large sheets comprising a frame having a deep horizontal throat open at one end to enable the insertion of the main body of the sheet into the throat, a horizontal cutter shaft extending longitudinally of the horizontal throat, a circular cutter mounted on said shaft adjacent the open end of the throat, driving means from said shaft adjacent the other end of the throat, a feed wheel mounted on said shaft adjacent said cutter, a second feed wheel opposite said first wheel and driven from said first feed wheel through the inner position of said sheet, a second circular cutter rotatable with said second feed wheel and cooperating with said first cutter, and manually operable means for shifting said second feed wheel and second cutter from a position in which the cutters are in overlapping shearing relation to a position in which the feed wheels and cutters are separated from each other to enable the insertion of the main body of the sheet between the cutters and feed wheels into the throat of the apparatus, said feed wheels being nearer to the closed end of the throat than are the cutters, whereby the feed wheels will act on the main body of the sheet material.
5. Apparatus for cutting gaskets from relatively large sheets comprising a frame having a deep horizontal throat open at one end to enable the insertion of the main body of the sheet into the throat, a pair of cooperating circular cutters mounted adjacent the open end of the throat, a longitudinal horizontal guide extending longitudinally of the horizontal throat, and a gasket centering pivot slidably adjustable on said guide to enable circular gaskets of various diameters to be formed by said cutters.

ALBERT WOOD.
